United States Patent Office

Des. 184,796
Patented Apr. 7, 1959

184,796

LAUNDRY BASKET OR SIMILAR ARTICLE

Charles O. Bliss, Los Angeles, Calif.

Application September 11, 1958, Serial No. 52,607

Term of patent 14 years

(Cl. D58—4)

Fig. 1 is a top plan view of a laundry basket or similar article showing my new design;

Fig. 2 is a side view thereof;

Fig. 3 is a bottom plan view thereof; and

Fig. 4 is a cross-sectional view thereof taken on the line 4-4 of Fig. 1 on an enlarged scale.

I claim:

The ornamental design for a laundry basket or similar article, substantially as shown.
